VAULT DOORS FOR BANKS AND BUSINESS INSTITUTIONS

Charles U. Deaton, Crestwood, Mo., assignor to Diebold, Incorporated, Canton, Ohio, a corporation of Ohio

Application March 19, 1953, Serial No. 343,368

8 Claims. (Cl. 109—64)

This invention relates in general to certain new and useful improvements in vault doors for banks and business institutions.

At the present time, banks and business institutions commonly employ large vaults in which money, valuables, records, and locked safe deposit boxes are placed for safekeeping. The vaults of this type are ordinarily quite large and during the day-time employees and other users walk in and out of the vault freely through the doorways thereto. Such vaults are provided with heavy massive steel doors which can be swung into closurewise position across the doorway and locked by combination-controlled locking means, carefully constructed to be burglar-proof, tamper-proof, and fire-proof. These doorways and door structures, generally, are made of alloy steel designed to resist the attack of drills, acetylene torches, and various other implements used by criminals in endeavoring to break into the closed safe or vault and, accordingly, are very heavy and cumbersome. Consequently, it is necessary to provide such doors with relatively rugged hinge structures and the doors, as such, are usually approximately as thick as the walls of the vault itself and are frequently marginally bevelled to provide greater security when closed.

All of these structural and safety problems make it necessary to provide a relatively wide arc of swing for the vault door, thereby consuming an unnecessarily large amount of floor space in front of the doorway which must be left free and unencumbered. Furthermore, conventional vault door hinges are pivoted at a relatively great distance from the center of gravity of the heavy mass or bulk of the door, so that when it is necessary to swing the door closed or swing it open, a great amount of manual force and effort is required to start the door in motion and, once the door is in motion, a similarly large amount of effort is required to stop it when it reaches or nears the limit of its travel and such energy must be exerted, because otherwise the door will slam shut with tremendous force, making a great deal of noise and even sometimes damaging the delicate mechanism of the combination.

Finally, most vault doors of the large heavy type are found in banks and, as is particularly true of safety deposit departments, the public can see the vault door when it is open. Since all vault doors presently in use swing open about a laterally positioned hinged point, the interior or back face of the door swings out and is exposed to view when the door is open. Consequently, it is necessary for manufacturers of vault doors to expend a considerable amount of time and expense in polishing the various parts of the vault door mechanism which are exposed on the rear or inside face of the door, so that, when the door is swung open and such parts come into view, the appearance of the structure will be attractive in the sense that it presents a finished and highly polished appearance. All of the gears which constitute the components of the time-lock combination and detent setting mechanism must be

2

highly polished and machined to present a desirable appearance.

It is, therefore, the primary object of the present invention to provide a vault door which is mounted on unique and novel hinge means, so that the door may be swung into and out of closed position with unusual ease and a minimum of manual effort.

It is another object of the present invention to provide a vault door which is so mounted that it will swing open through an arc of movement, requiring much less floor space and clearance than conventional doors.

It is an additional object of the present invention to provide a vault door which is uniquely mounted for swinging movement in such a manner that the face of the door, which is presented outwardly when the door is closed, will at all times remain in outwardly presented position as the door is being swung open and as it reaches its fully opened position, so that only the finished outer face of the door is ever exposed to public view.

With the above and other objects in view, my invention resides in the novel features of form, construction, arrangement, and combination of parts presently described and pointed out in the claims.

In the accompanying drawings (two sheets)—

Figure 1 is a fragmentary front elevational view of a vault doorway having a vault door constructed in accordance with and embodying the present invention and showing the vault door in closed position;

Figure 2 is a fragmentary front elevational view of a vault doorway having a vault door constructed in accordance with and embodying the present invention and showing the vault door in fully opened position;

Figures 3, 4, and 5 are fragmentary sectional views taken along lines 3—3, 4—4, and 5—5, respectively, of Figure 1;

Figure 6 is a horizontal sectional view of the vault wall showing the vault door of the present invention in fully opened position;

Figure 7 is a fragmentary front elevational view of a vault wall having a modified form of vault door constructed in accordance with and embodying the present invention; and

Figures 8, 9, and 10 are fragmentary horizontal sectional views of the vault wall and vault door construction of Figure 7, respectively showing the vault door in fully closed, partially opened, and fully opened positions.

Referring now in more detail and by reference characters to the drawings, which illustrate practical embodiments of the present invention, A designates a conventional vault wall of heavy reinforced steel, concrete and masonry construction having a door opening 1 bounded or framed by a conventional steel frame 2 having a series of lateral recesses 3 for conventionally receiving the sliding bolts 4. Inasmuch as the locking mechanism of the safe which actuates the bolts 4 and operatively connects them with the combination are conventional and do not constitute a part of the present invention, such mechanism is not specifically shown or described in detail herein, it being merely sufficient to say that the vault door 5 is locked thereby when in closed position and contains a conventional combination knob 6 by which the bolts 4 may be locked in place when the vault door 5 is closed.

The vault door 5 is also provided with a conventional lock operating handle 7 by which the bolts 4 are slid into and out of locked position when the combination 6 is off.

Bolted or otherwise suitably mounted upon the rear or inwardly presented face 8 of the vault door 5 is a hinge-bracket 9 having two laterally spaced vertical hinge pins 10, 11, and similarly mounted upon the interior face of

the vault wall A, adjacent to the vertical margin of the door opening 1, is a second hinge-bracket 12 also having laterally spaced vertical hinge pins 13, 14. Swingably mounted at its opposite ends upon and extending transversely between the hinge pins 10, 13, is a large hinge link 15 having somewhat L-shaped horizontal cross-sections conforming to the horizontal cross-section of the edge of the vault door and wall, as shown in Figure 6. Similarly mounted at its opposite ends and extending horizontally between the hinge pins 11, 14, is a main hinge plate 16 also of somewhat L-shaped horizontal cross-sectional shape and adapted likewise to fit snugly against the contour of the edge of the doorway 1, as shown in Figure 6. It should be noted in this connection that the main hinge plate 16 is of relatively long heavy construction and supports the entire weight of the door 5, the link 15 serving merely as a stabilizing mechanism to maintain the door parallel to the plane of the door opening throughout all positions of swinging movement, substantially as shown in Figures 4, 5, and 6.

When the vault is closed, the vault door 5 will be positioned in the opening, substantially as shown in Figure 1, with the combination 6 and lock operating handle 7 in forwardly presented position. The vault door 5 is preferably provided with a conventional pull handle 17, which is located upon the forward face of the vault door 5 preferably in line with the hinge pin 11. When the vault door 5 is unlocked, it may be pulled straight outwardly by grasping the handle 17 and, as outward pulling movement is continued, will swing clear of the door opening 1 and move laterally across and in front of the outwardly presented face of the vault wall A along a flat arc of comparatively short radius, as shown in dotted lines in Figures 4 and 6, and will assume a position completely to one side of the door opening flatwise against the outer face of the vault wall A, as shown in Figure 6. When it is necessary to close the vault, the vault door 5 may be swung back into initial position by reversing this sequence of movements.

If desired, it is possible to provide a modified form of vault door 5', which is substantially similar in all respects to the previously described vault door 5, having hinge-brackets 9', 12', hinge pins 10', 11', 13', 14', a hinge link 15', and a hinge plate 16', all substantially similar to the corresponding elements of the previously described vault door 5. The main hinge plate 16', however, is recessed, as at 18, and is provided with a tooth-forming laterally projecting tongue 19 for optional engagement within the threads of a short relatively heavy worm 20 pinned upon the inner end of a handle shaft 21 journaled in and extending through the vault door 5' and provided on its external end with a handle 22. As will be seen in Figure 7, the handle 22 preferably includes three radial spokes 23 arranged at 120° intervals around its periphery, one of the spokes 23 being adapted to assume a downwardly extending vertical position when the in-leading end of the worm 20 is set to clear the tongue 19. Thus, when the vault door 5' is open, the worm 20 and tongue 19 will be completely disengaged, as shown in Figure 10. When, however, the vault door 5' is swung into closed position, as shown in Figure 8, the tongue 19 will swing down into engagement within the in-leading end of the worm 20, the latter being positioned so that it will readily receive the tongue 19 by positioning the handle 22 in the manner above described. Thereupon, the handle 22 may be rotated so as to draw the tongue 19 down into the worm, pulling the vault door 5' tightly into fully seated closed position, as shown in Figure 8.

When the vault door 5' is opened, the handle 22 is rotated in the reverse direction, swinging the vault door outwardly through an initial forward portion of its movement and as the tongue 19 becomes disengaged from the

worm 20, the vault door 5' is free to be manually swung into fully opened position.

The worm 20 and tongue 19 make it possible to pull the vault door 5' into and out of tightly sealed position without the use of complicated camming mechanisms commonly found at the present time in conventional vault door structures.

It should be understood that changes and modifications in the form, construction, arrangement, and combination 10 of the several parts of the vault door may be made and substituted for those herein shown and described without departing from the nature and principle of my invention.

Having thus described my invention, what I claim and desire to secure by Letters Patent is:

- 15 1. A safety and protective doorway for vaults, safes, and the like comprising a wall having exterior and interior faces and a door-opening therein, the front and rear peripheral margins of the door-opening lying in parallel planes, a substantially flat door sized and shaped 20 for snug-fitting closure-forming engagement within the door-opening, said door having an interior and an exterior face, a link pivotally secured at one end to the interior face of the door and pivotally secured at its other end to the interior face of the wall whereby the door can be 25 swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit conformably around the edges of the doorway when the door is open and being pivotally connected at its ends respectively to the interior faces of the door and wall 30 at points which are laterally spaced in relation to the hinge points of the first-named link to hold the door substantially parallel to its initial position throughout its arc of swing, one of said links being provided with a projecting tooth, a shaft rotatably mounted in the door and projecting at its rear end from the interior face of the 35 door adjacent to said projecting tooth, and means rigidly mounted on the projecting end of the shaft for optionally engaging the tooth as the door approaches closed position whereby to draw the door tightly into such closed position.
- 40 2. A safety and protective doorway for vaults, safes, and the like comprising a wall having exterior and interior faces and a door-opening therein, the front and rear peripheral margins of the door-opening lying in parallel planes, a flat door sized and shaped for snug-fitting closure-forming engagement within the door-opening, said door having an interior and an exterior face, a link pivotally secured at one end to the interior face of the door and pivotally secured at its other end to the interior face of the wall whereby the door can be 45 swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit conformably around the edges of the doorway when the door is open and being pivotally connected at its ends respectively to the interior faces of the door and wall 50 at points which are laterally spaced in relation to the hinge points of the first-named link to hold the door substantially parallel to its initial position throughout its arc of swing, one of said links being provided with a projecting tooth, a shaft rotatably mounted in the door and projecting at its rear end from the interior face of the door adjacent to said projecting tooth, and means rigidly mounted on the projecting end of the shaft for optionally 55 engaging the tooth as the door approaches closed position whereby to draw the door tightly into such closed position.
- 55 3. A safety and protective doorway for vaults, safes, and the like comprising a wall having exterior and interior faces and a door-opening therein, the front and rear peripheral margins of the door-opening lying in parallel planes, a flat door sized and shaped for snug-fitting closure-forming engagement within the door-opening, said door having an interior and an exterior face, a link pivotally secured at one end to the interior face of the door and pivotally secured at its other end to the interior face of the wall whereby the door can be 60 swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit conformably around the edges of the doorway when the door is open and being pivotally connected at its ends respectively to the interior faces of the door and wall 65 at points which are laterally spaced in relation to the hinge points of the first-named link to hold the door substantially parallel to its initial position throughout its arc of swing, one of said links being provided with a projecting tooth, a shaft rotatably mounted in the door and projecting at its rear end from the interior face of the door adjacent to said projecting tooth, and means rigidly mounted on the projecting end of the shaft for optionally 70 engaging the tooth as the door approaches closed position whereby to draw the door tightly into such closed position.
- 75 3. A safety and protective doorway for vaults, safes,

and the like comprising a wall having exterior and interior faces and a door-opening therein, the front and rear peripheral margins of the door-opening lying in parallel planes, a flat door sized and shaped for snug-fitting closure-forming engagement within the door-opening, said door having an interior and an exterior face, a link pivotally secured at one end to the interior face of the door and pivotally secured at its other end to the interior face of the wall whereby the door can be swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit conformably around the edges of the doorway when the door is open and being pivotally connected at its ends respectively to the interior faces of the door and wall at points which are laterally spaced in relation to the hinge points of the first-named link to hold the door substantially parallel to its initial position throughout its arc of swing, one of said links being provided with a projecting tooth, a shaft rotatably mounted in the door and projecting at its rear end from the interior face of the door adjacent to said projecting tooth, and a worm rigidly mounted on the projecting end of the shaft for optionally engaging the tooth as the door approaches closed position whereby to draw the door tightly into such closed position.

4. A safety and protective doorway for vaults, safes, and the like comprising a wall having exterior and interior faces and a door-opening therein, the front and rear peripheral margins of the door-opening lying in parallel planes, a flat door sized and shaped for snug-fitting closure-forming engagement within the door-opening, said door having an interior and an exterior face, a link pivotally secured at one end to the interior face of the door and pivotally secured at its other end to the interior face of the wall whereby the door can be swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit conformably around the edges of the doorway when the door is open and being pivotally connected at its ends respectively to the interior faces of the door and wall at points which are laterally spaced in relation to the hinge points of the first-named link to hold the door substantially parallel to its initial position throughout its arc of swing, one of said links being provided with a projecting tooth, a shaft rotatably mounted in the door and projecting at its rear end from the interior face of the door adjacent to said projecting tooth, and an open-ended worm rigidly mounted on the projecting end of the shaft for optionally engaging the tooth as the door approaches closed position whereby to draw the door tightly into such closed position.

5. A safety and protective doorway for vaults, safes, and the like comprising a wall having exterior and interior faces and a door-opening therein, the front and rear peripheral margins of the door-opening lying in parallel planes, a flat door sized and shaped for snug-fitting closure-forming engagement within the door-opening, said door having an interior and an exterior face, a link pivotally secured at one end to the interior face of the door and pivotally secured at its other end to the interior face of the wall whereby the door can be swung into and out of closure-forming position, said link integrally comprising a long leg and a short leg transversely connected in spaced parallel relationship by an intermediate member, said link being so shaped as to fit conformably around the edges of the doorway when the door is open, another link also shaped so as to fit

conformably around the edges of the doorway when the door is open and being pivotally connected at its ends respectively to the interior faces of the door and wall at points which are laterally spaced in relation to the hinge points of the first-named link to hold the door substantially parallel to its initial position throughout its arc of swing, one of said links being provided with a projecting tooth which swings along an arc concentric with its pivot point on the door, a shaft rotatably mounted in and extending through the door, and a worm fixed upon the inner end of the shaft and having an inwardly presented open-ended thread, the open end of which lies in the path of arcuate movement of the tooth as the link with which it is associated pivots during opening and closing movement of the door for optionally engaging the tooth as the door approaches closed position so that the door can be drawn tightly into such closed position by rotation of the shaft.

6. A safety and protective doorway for vaults, safes, and the like comprising a wall of substantial thickness having exterior and interior faces and a door-opening, said door-opening having at least one substantially vertical margin, the front and rear peripheral margins of the door-opening lying in parallel planes so that the door-opening is bounded by an inter-wall face of substantial width, said exterior, interior, and inter-wall faces conjointly conforming to a selected horizontal cross-sectional contour along said vertical margin of the door-opening, a door sized and shaped for snug-fitting closure-forming engagement within the door-opening, said door having an interior and an exterior face, a first substantially L-shaped link having a long leg and a short leg connected by a transverse bight and conforming in shape to the horizontal cross-sectional contour of the door-opening, said link being pivotally secured at one end to the interior face of the door and pivotally secured at its other end to the interior face of the wall whereby the door can be swung into and out of closure-forming position, and a second L-shaped link having a long leg and a short leg connected by a transverse bight and conforming in shape to the horizontal cross-sectional contour of the door-opening, the long and short legs of said second link being respectively longer than the long and short legs of the first link, said second link also being pivotally connected at its ends respectively to the interior faces of the door and wall at points which are laterally spaced in relation to the hinge points of the first-named link, said hinge points all lying in a single plane which is parallel to the interior faces of the wall and door when the door is in closed position to hold the door substantially parallel to its initial position throughout its arc of swing.

7. A safety and protective doorway for vaults, safes, and the like comprising a wall of substantial thickness having exterior and interior faces and a door-opening, said door-opening having at least one substantially vertical margin, the front and rear peripheral margins of the door-opening lying in parallel planes so that the door-opening is bounded by an inter-wall face of substantial width, said exterior, interior, and inter-wall faces conjointly conforming to a selected horizontal cross-sectional contour along said vertical margin of the door-opening, a door sized and shaped for snug-fitting closure-forming engagement within the door-opening, said door having an interior and an exterior face, a first link having a long and a short leg connected by a transverse bight and being pivotally secured at one end to the interior face of the door and pivotally secured at its other end to the interior face of the wall whereby the door can be swung into and out of closure-forming position, said link having a profile geometrically conformable to the transverse cross-sectional shape of the wall across the edge of the doorway, and a second link having a long leg and a short leg connected by a transverse bight, the long and short legs of said second link being respectively longer than the cor-

responding legs of the first link, said second link being also geometrically conformable to the transverse cross-sectional shape of the wall across the edge of the doorway and being pivotally connected at its ends respectively to the interior faces of the door and wall at points which are laterally and vertically spaced in relation to the hinge points of the first-named link, the hinge points of the two links on the interior face of the wall being at all times located in a single plane which is parallel to such interior face of the wall, the hinge points on the door similarly lying in a single plane which is at all times parallel to the interior face of the door whereby to hold the door substantially parallel to its initial position throughout its arc of swing and the first and second links are nested in close-fitting relationship around the interior wall face of the door-opening and in vertically aligned position with respect to each other.

8. A safety and protective doorway for vaults, safes, and the like comprising a wall of substantial thickness having exterior and interior faces and a door-opening, said door-opening having at least one substantially vertical margin, the front and rear peripheral margins of the door-opening lying in parallel planes so that the door-opening is bounded by an inter-wall face of substantial width, said exterior, interior, and inter-wall faces conjointly conforming to a selected horizontal cross-sectional contour along said vertical margin of the door-opening, a door sized and shaped for snug-fitting closure-forming engagement within the door-opening, said door having an interior and an exterior face, a first link pivotally secured at one end to the interior face of the door and pivotally secured at its other end to the interior face of the wall whereby the door can be swung into and out of closure-forming position, said link integrally comprising a long leg and a short

leg transversely connected in spaced parallel relationship by an intermediate member, said link being so shaped as to fit conformably around the edges of the doorway when the door is open, and a second link also shaped so as to fit conformably around the edges of the doorway when the door is open and including a long leg and a short leg transversely connected in space-parallel relationship by an intermediate member, the long and short legs of said second link being respectively longer than the corresponding legs of the first link, said second link also being pivotally connected at its ends respectively to the interior faces of the door and wall at points which are laterally and vertically spaced in relation to the hinge points of the first-named link so that when the door is closed, the first and second links will be one above the other and the long leg of the second link will cross the bight of the first link, whereby to hold the door substantially parallel to its initial position throughout its arc of swing, the hinge points on the door being co-planar with respect to each other and the hinge points on the wall similarly being co-planar with respect to each other.
